UNITED STATES PATENT OFFICE.

WILLIAM J. PATTERSON, OF PITTSBURG, PENNSYLVANIA, ASSIGNOR TO
HEYL & PATTERSON, OF PITTSBURG, PENNSYLVANIA, A PARTNERSHIP
OF PENNSYLVANIA.

COAL-BREAKER.

SPECIFICATION forming part of Letters Patent No. 770,819, dated September 27, 1904.

Application filed December 19, 1903. Serial No. 185,812. (No model.)

To all whom it may concern:

Be it known that I, WILLIAM J. PATTERSON, a resident of Pittsburg, in the county of Allegheny and State of Pennsylvania, have invented 5
5 a new and useful Improvement in Coal-
Breakers; and I do hereby declare the following
to be a full, clear, and exact description
thereof.

My invention relates to coal-breakers, and
10 more particularly to that class of coal-breakers
comprising a rotary cylinder having
shelves therein which are adapted to lift the
coal and drop it as the cylinder revolves, so
that the coal is broken and that which is of
15 the proper degree of fineness falls through
perforations in said cylinder, while the slate,
sulfur balls, or harder substances are dis-
charged from one end of the cylinder, so as
not to mix with the screened coal.
20 The object of my invention is to provide a
coal-breaker like the above in which the
breaking up of the slate, sulfur balls, or other
harder substances to the same degree of fine-
ness as the coal is prevented, so that such im-
25 purities will not pass through the perfora-
tions and be mixed with the coal so broken.

To these ends my invention consists, generally stated, in a coal-breaker having a shelf
30 extending longitudinally thereof adapted to
lift the coal and other substances within the
breaker and means for varying the length of
said shelf according to the requirements of
the substances to be separated.

To enable others skilled in the art to make
35 and use my invention, I will describe the same
more fully, referring to the accompanying
drawings, in which—

Figure 1 is a front elevation of my improved
breaker, partly in section. Fig. 2 is an en-
40 larged front view of the cylinder, partly broken
away and in section. Fig. 3 is an enlarged
cross-section of the shelf of my improved
breaker, the extension and cylinder being
45 shown in section; and Fig. 4 is a longitudinal
rear view of the shelf, partly in section.

Like numerals indicate like parts in each
view.

As stated above, my invention relates to
that class of coal-breakers in which a cylin-

der is employed with shelves adapted to lift 50
the coal and drop the same, so as to be broken,
the coal passing through perforations in said
cylinder and the impurities being carried to
and discharged at the end of said cylinder.
I have accordingly illustrated my invention 55
in connection with such a breaker, and as my
invention relates particularly to the shelf
construction it will only be necessary to de-
scribe in general the construction of the
breaker illustrated. 60

The numeral 2 designates a suitable sup-
port for the breaker-frame 3. The cylinder 4
is provided with the journals 5, supported in
the frame 3, said cylinder having the cog-
wheel 6, with which the pinion 7 on the shaft 65
8 meshes. This shaft 8 has the pulley 9, which
may be connected up to any suitable source of
power. In this manner a rotary movement
is imparted to the cylinder 4. The cylinder
4 is made up of the circular perforated plates 70
10, which are connected by the inner and
outer strips 11 11^a, respectively, secured by
the bolts 12.

Within the cylinder 4 are the shelves 13,
said shelves having the curved portion 14, 75
with the lugs 15, adapted to enter correspond-
ing seats in the blocks 16. The shelves 14
are secured in place by means of the bolts 17
passing through the curved portion 14, the
blocks 16, and through the perforated plates 80
10 of the cylinder. These bolts also pass
through the outer strips 11. These shelves
secured in this manner extend with their main
portion substantially the length of the cylin-
der and are provided with the lengthwise-ad-
justable extension 19. This extension 19 is 85
provided with the slots 20 21 and is secured
to the main portion of the shelf by means of
the bolts 22 and 23, the bolts 22 passing
through the slot 20 and the bolts 23 through 90
the slot 21 in the flange 19^a. By tightening
up the nuts 24 on said bolts the extension 19
is securely attached to the shelf proper. These
shelves may be arranged at suitable intervals
within the cylinder as may be found necessary. 95

Secured within the cylinder at proper in-
tervals are the guiding-blocks 25, said guid-
ing-blocks being arranged with reference to

each other so as to form spiral grooves within the cylinder, so that in the rotation of the cylinder these grooves will tend to carry the coal from the feeding end of the cylinder to the discharge end. These guiding-blocks 25 are held in place by means of bolts 25^a, and the angle of these blocks may be varied according as it is desired to feed the coal more rapidly from the feed end to the discharge end of the cylinder. The cylinder is provided with the discharge-head 26, and in order to direct the impurities or refuse to this discharge the spiral chute 27 is employed.

Connected to the feed end 28 of the breaker 15 is the chute 29, which is connected with the feeder 30. This feeder may be of ordinary construction and as it forms no part of my invention needs no further description.

A hopper 31 is connected to the feeder 30. 20 The coal to be broken is fed to the hopper 31 and passing through the feeder 30 is discharged into the chute 29, whence it passes into the cylinder 4. As the cylinder rotates the coal is carried up by the shelves 13, and 25 when the shelf passes beyond a certain point the coal is dropped into the cylinder and by the force of its fall is broken. That portion of the coal which is of the proper degree of fineness passes through the perforations, while 30 the larger pieces are again lifted by the next succeeding shelf and dropped in the same manner. In the meantime the coal has been fed toward the discharge end of the machine by the action of the spirally-arranged guiding-blocks 25, and by the time the coal has reached 35 the discharge end all will have been broken to the proper degree of fineness to pass through the perforations, with the exception of the slate and sulfur balls, which are of a harder 40 quality, and these will pass out through the spiral chute 27 to be discharged from the discharge end 26 of the cylinder.

If in the operation of the machine it is found that the harder substances are being reduced 45 to such degree of fineness as to pass through the perforations with the coal and it is desired to prevent this, the bolts 22 and 23 are loosened and the extension 19 of the shelf is moved

back a proper distance to reduce the length of the shelf. The bolts are now adjusted and 50 the machine put in operation, when it will be apparent that by the shortening of the shelf the substances will not be lifted so often by the shelves, and consequently not subjected to so many falls. The material instead of being lifted by the shelf after it passes beyond the same will merely be given a tumbling-barrel action throughout the last portion of the cylinder. By my improvement, therefore, 55 it is possible to regulate the machine to a 60 nicety, and the same machine may be used for coal of different quality, so that the mixing of the impurities with the coal is prevented.

What I claim is—

1. In a coal-breaker, the combination of a 65 rotary cylinder, a shelf extending longitudinally thereof, and means for varying the length of said shelf.

2. In a coal-breaker, the combination of a 70 rotary cylinder, a shelf extending longitudinally thereof, and a movable section on said shelf.

3. In a coal-breaker, the combination of a 75 rotary cylinder, a shelf extending longitudinally thereof, a movable section on said shelf, and means for securing said section in place at different positions on said shelf.

4. In a coal-breaker, the combination of a 80 rotary cylinder, a shelf extending longitudinally thereof having a slot formed therein, a section having a slot, and bolts passing through 85 said slots.

5. In a coal-breaker, the combination of a 90 rotary cylinder, a shelf extending longitudinally thereof having a slot formed therein, a section having a slot, bolts passing through said slots, said section having a flange having a slot therein coinciding with an opening formed in said cylinder, and bolts securing said flange to said cylinder.

In testimony whereof I, the said WILLIAM J. PATTERSON, have hereunto set my hand.

WILLIAM J. PATTERSON.
